3 Claims. (Cl. 339—192)

This invention relates to electrical socket devices and particularly to a socket unit of novel form for electrical connection with an electric discharge device of the type known as a cavity resonator.

One object of my invention is the provision of a socket assembly comprising a socket body carrying prong-receiving terminals and a mounting member secured to the socket body and providing an attaching portion in fastened engagement with the resonator device to assist maintenance of the electrical connection between the prong terminals of the resonator and the contacts of the socket body.

Another object is the provision of a mounting member which not only aids attachment of the socket to the resonator, but also electrically engages the cathode conductor of the resonator so as to effect a soldering terminal for grounding the cathode.

Still another object of my invention relates to a socket assembly comprising a socket body and a mounting member in which the mounting member is easily and efficiently moved into attachment to the socket body.

Referring to the drawings in which I have illustrated preferred embodiments of my invention;

Fig. 1 is a fragmentary front plan view partly in section of an electrical connection embodying my invention and including an electronic tube which is preferably a cavity resonator electrically engaged with an improved socket device;

Fig. 2 is a plan view of the terminal end of the cavity resonator per se;

Fig. 3 is an exploded front plan view of the parts of the socket device prior to assembly;

Fig. 4 is a side view of the parts of the socket device in assembled relation;

Fig. 5 is a section taken along the line 5—5 of Fig. 4;

Fig. 6 is a top view of the mounting member of the socket device;

Fig. 7 is a front plan view of a modified form of mounting member;

Fig. 8 is a plan view of a modified form of socket body.

Referring to the installation illustrated in Fig. 1, I have shown a plug unit in the form of an electronic tube 1 of the type known as a cavity resonator. The tube 1 provides an outer metal shell 2 closed at its lower end by a cup shaped metal stamping 3 which is insulated from the shell 2 by a band of insulating material 4. The base 5 of the member 3 has a tubular conductor 6 which is drawn from the base 5 and extends downwardly therefrom. The conductor 6 is in soldered engagement with a sleeve member 7 which has resilient fingers 8 at its upper end in electrical engagement with the tubular cathode lead 9 which projects beyond the lower end of the conductor 6. As a result of the construction of the cavity resonator, the tubular conductor 6 is electrically connected to the cathode lead 9 through the sleeve member 7. The cavity resonator has a pair of prong-like heater leads 10 which are disposed within the cathode lead 9 and insulated from the cathode by dielectric material 11. The terminals 10 project below the outermost end of the cathode 9 for electrical engagement with socket contact elements carried by a cooperating socket body. The cavity resonator of my preferred installation also provides a pair of exhaust terminals 12 the ends of which may project slightly beyond the lower end of the cathode 9. The exhaust terminals 12 are insulated from the heater terminals 10 and the cathode 9 by the insulating material 11.

The socket device in my preferred embodiment com-

2

prises a socket body 13 of insulating material which is preferably of cylindrical form having a pair of openings 14 (Fig. 5) in its upper end 13a for receiving the heater terminals 10. A socket contact 15 is secured in each of the openings 14 and each contact provides a prong-engaging portion 16 adapted to receive and grip electrically a heater terminal 10. The contact 15 has a soldering tail 17 extending beyond the exterior surface of the socket body 13 to enable a lead wire to be soldered thereto. The socket body 13, in my preferred form, has a second pair of openings 18 (Fig. 5) extending into the upper end 13a of the socket body a predetermined distance to receive the outer ends of the exhaust leads 12 when the parts of the installation are in assembly. My preferred form of socket body 13 has a rectangular projection 19 disposed on the exterior surface 20 of the socket body and positioned approximately half way between the upper and lower ends of the socket body. The projection 19 operates to lock the socket body in assembly with the mounting member of the socket device as will be hereinafter described.

The mounting member 21 of the socket device is a clip-like member formed of one piece of spring metal and provides a lower resilient ring-like element 22 and an upper resilient ring-like element 23. The ring-like elements 22 and 23 are disposed in axial alignment one above the other and integrally joined by the base portion 24 of the mounting member which is common to both ring-like elements. The lower ring-like element 22 has a diameter which is normally less than the diameter of the socket body 13 and provides a slot 25 in its side opposite the base 24 which extends axially from its upper end 26 to its lower end 27. The width of the slot 25 is normally less than the width of the projection 19 of the socket body for a purpose to be described. A notch or opening 29 is provided in each of the edges 28 of the ring-like element 22 adjacent the slot 25. The openings 29 are disposed in opposite relation and cooperate to receive the projection 19 of the socket body when the socket body is assembled with the mounting member as will be described. In my preferred embodiment, a radius 30 is provided at the ends of the edges 28 adjacent the ends 26 and 27 of the ring-like element. These radii effect leads for facilitating entrance of the projection 19 into the slot 25 during assembly of the socket body with the mounting member. The upper ring-like element 23 is preferably of larger diameter than the lower ring-like element 22 and is made resilient by provision of a slot 31 disposed on an opposite side of an element from the base 24 and extending from the upper end 32 of the element 23 to the lower end 33. The element 23 has a diameter normally smaller than the diameter of the conductor 6 for a purpose to be described. The upper end 32 of the ring-like element 23 may be flared as at 34 so as to effect a lead for attachment of the ring-like element 23 to the tubular conductor 6 of the tube 1. In view of the fact that the mounting member 21 acts as a ground connection as well as a fastener, it has a terminal soldering tail 35 which in my preferred form is integrally joined to the lower end 27 of the ring-like element 22.

In the preferred method of assembling the parts of the socket device, the socket body 13 is moved into the lower end of ring-like element 22 with the projection 19 in alignment with the slot 25. During this action the projection 19 will engage the edges 28 of the ring-like element 22 and expand the same permitting the projection 19 to move upwardly along the slot 25 until it is received within the openings 29—29. When the projection 19 is in this position, the portions of the ring-like element 22 contract so that the shoulders 36 formed at the upper and lower ends of the notches 29—29 overlie and underlie the respective upper and lower ends of the projection 19 to resist movement of the socket body 13 axially of the element 22 in either an upward or downward direction. As a result of the fact that the normal diameter of the ring-like element 22 is less than the normal diameter of the socket body 13, the ring-like element 22 will operate to grip resiliently the exterior surface 20 of the socket body thereby to hold the socket body in firm, locked assembly. The socket body may be removed from assembly with the ring-like element 22, if it should be necessary,

by prying the edges 25 of the ring-like element 22 apart to permit the projection 19 of the socket body to be moved out of the slot 25 at one end of the ring-like element.

The socket device comprising the mounting member and the socket body assembled therewith, is attached to the tube 1 by aligning the heater terminals 10 with the openings 14 of the socket body and then moving the ring-like element 23 of the mounting member over the tubular conductor 6 until the outermost end 37 of the tube unit abuts or is disposed in close adjacency to the upper end 13a of the socket body 13. The parts are now in assembled relation with the heater terminals 10 in electrical connection with the contacts 15 carried by the socket body 13. At the same time the outer ends of the exhaust terminals 12 will be disposed in the openings 18 of the socket body. In order to insure alignment of the heater terminals 10 with the socket contacts 15 when the socket device is moved into assembly with the tube, the socket device is turned so that the plane of a line through the center of the locking projection 19 axially of the socket body coincides with an imaginary line connecting the two heater terminals 10. As a result of the fact that the ring-like element 23 normally has a diameter less than the diameter of the tubular conductor lead 6, the ring-like element 23 will expand during movement over the lead 6 to engage frictionally the lead 6 and thereby secure the socket device in firm attachment to the tube 1. At the same time, the frictional engagement between the ring-like element 23 and the tubular conductor lead 6 will effect a firm electrical engagement between the parts with the result that the mounting member provides an electrical connection between the cathode of the tube and a lead wire (not shown) soldered to the tail 35 of the mounting member.

A modified construction of my socket device is illustrated in Figs. 7 and 8. In the modified form, the projection 19 is omitted from the cylindrical socket body 38 with the result that the socket body has a smooth exterior surface. My modified form of mounting member 39 is generally similar to the mounting member 21 of my first form and provides upper and lower ring-like elements 40 and 41 respectively. The ring-like element 40 has a slot 42 and the ring-like element 41 has a slot 43 each of which extends axially from one end to the other of its respective ring-like element to effect resiliency. The edges of the ring-like element 41 adjacent the slot 43 are not notched as in the ring like element 22 of my first form with the result that the socket body 38 is maintained in assembly with the ring-like element 41 solely through the frictional forces which the ring-like element 41 exerts on the exterior surface of the socket body 38. It has been found that in some installations this frictional engagement between the parts without a locking means serves to maintain efficiently the parts in assembly.

In the preferred method of assembling my second form of socket device with the tube 1, the socket body 38 is first moved toward the terminal end of the tube 1 to engage the socket contacts 44 carried thereby with the heater terminals 10 of the tube. The engagement between the terminals 10 and the socket contacts 44 operates to hold the parts in initial attached assembly. Thereafter, the ring-like element 40 of the mounting member 39 is moved over the socket body 38 to embrace frictionally the tubular conductor 6. At the same time, the ring-like element 41 will move over the socket body 38 to grip resiliently the same and hold the socket body in firm as-

sembly with the tube 1. The socket body 38 is preferably provided with an annular radius 45 at its lower end 46 to assist passage of the socket body into the ring-like element 41 during the assembly operation just described.

5 The socket body 38 may also have an annular radius 47 at its upper end 48 to facilitate entrance of the socket body into the ring-like element 41 should it be desired to assemble the socket body with the mounting member prior to moving the mounting member and the socket body as a unit into assembly with the tube 1.

10 Although I have illustrated and described preferred embodiments of my invention, I do not wish to be limited thereby because the scope of my invention is best defined by the following claims.

15 I claim:

1. An electrical socket device comprising a socket body of insulating material carrying contact members for receiving prong terminals, said body having a locking element projecting from its exterior surface, and a metal

20 mounting member for holding said socket body in assembly with a cooperating plug unit, said mounting member having a ring-like element resiliently embracing the exterior surface of said socket body, said ring-like element having an opening receiving said projection in interlocking connection, and an attaching element integral with said mounting member for attachment to said plug unit.

25 2. An electrical socket device comprising a socket body of insulating material carrying contact members for receiving prong terminals, said body having a locking element projecting from its exterior surface, and a metal

30 mounting member for holding said socket body in assembly with a cooperating plug unit, said mounting member providing a ring-like element resiliently embracing the exterior surface of said socket body, said ring-like element

35 having a slot extending axially from end to end, an edge of said ring-like element adjacent said slot having an opening therein, said locking element being received in said slot during assembly of said socket body with said ring-like element, said locking element being of greater width than said slot to expand said ring-like element during said assembly to engage said locking element in assembly with said ring-like element within said opening, and an attaching element integral with said ring-like element for attachment to said plug unit.

40 45 3. The device described in claim 2 in which said attaching element is in the form of a second ring-like element having an axial passage in alignment with the axial passage of said ring-like element embracing said socket body.
